(57) **CLAIM**

The ornamental design for an ostomy bag, as shown and described.

DESCRIPTION

FIG. 1 is an isometric view of an ostomy bag having a bag portion and an outlet tail with covering over the bag portion. The drawing is lined for the color gray.

FIG. 2 is a front side view of the ostomy bag of FIG. 1; FIG. 3 is a back side view of the ostomy bag of FIG. 1; FIG. 4 is a right side view of the ostomy bag of FIG. 1, where a left side view is not illustrated as it is a mirror image of the right side view;

FIG. 5 is a top side view of the ostomy bag of FIG. 1; FIG. 6 is a bottom side view of the ostomy bag of FIG. 1; and FIG. 7 is a front side view of the ostomy bag of FIG. 1 with the outlet tail folded and secured; and,

FIG. 8 is an isometric view of the ostomy bag of FIG. 1 illustrating the front face of the bag portion in an expanded condition from the rear face of the bag portion.

FIGS. 1-3 and 7-8 are lined for color.

In FIGS. 1-4 and 6-8 the broken lines illustrate an outlet tail of embodiments of an ostomy bag and form no part of the claimed design.

In FIGS. 3-6 the broken lines illustrate an inlet hole for the ostomy bag and an attachment wafer attached to the ostomy bag, the inlet hole and the attachment wafer form no part of the claimed design.

1 Claim, 7 Drawing Sheets
